UNITED STATES PATENT OFFICE.

CHARLIE O. LOUTHAN, OF KANSAS CITY, KANSAS.

SIGNALING DEVICE.

1,223,060.

Specification of Letters Patent. Patented Apr. 17, 1917.

Application filed May 16, 1916. Serial No. 97,801.

To all whom it may concern:

Be it known that I, CHARLIE O. LOUTHAN, a citizen of the United States, residing at Kansas City, in the county of Wyandotte and State of Kansas, have invented certain new and useful Improvements in Signaling Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to burglar alarms for automobiles and has for its principal object to provide a device of this character whereby the owner of an automobile may be warned should any one, other than one authorized, tamper with, or attempt to start the machine.

In accomplishing this object, I have provided the details of structure hereinafter described and illustrated in the accompanying drawings, wherein:—

Figure I is a perspective view of an automobile equipped with my invention showing the disposition of the contact members within the hood of the automobile and their connecting wires.

Fig. II is a diagrammatic view showing the contact members, the battery and signaling device and their connecting wires.

Fig. III is a detail perspective view, illustrating the mounting of the magnetic coil within its housing, the contact post and plates and wires connecting therewith.

Fig. IV is a perspective view of the contact plates for closing a circuit through the alarm when released by the throttle mechanism.

Fig. V is a detail perspective view of one set of contact plates, which are adapted for closing a circuit through the horn motor when released by the opening of the hood doors.

Fig. VI is a sectional view through the battery box, showing the means for closing a circuit through the alarm by raising the box end.

Fig. VII is a detail perspective view of the lock for closing or breaking a circuit through the system.

Referring more in detail to the drawings:—

1 designates the hood of an automobile

of ordinary construction and having side opening hood doors, 2, a dash board 3, steering posts 4, and a throttle adjusting arm 5, which is operable from the steering wheel 60 position to open or close the throttle valve of the motor (not shown).

Mounted at any desirable place on the machine, preferably at the side thereof, is a housing 6 for containing a battery 7, which is connected by wires as will presently be described with the motor 8 of an electrically operated horn 9, by which the owner of the car may be alarmed should an unauthorized person attempt to start the machine or tamper with the mechanism; the horn preferably being concealed within a perforated housing 10, carried within the hood on the automobile frame member 11.

Leading from the positive pole of the 75 battery 7, through a conduit 12, which extends from the battery housing to a housing 13 that is mounted on the dash and concealed within the hood is a circuit wire 14, which connects within the housing to one 80 pole of a magnetic solenoid coil 16.

Interposed in the circuit wire 14 between its connection with the battery 7 and coil 16, is a lock 17, which may be mounted at any convenient place in the dash 3, so that 85 it is accessible from the driver's seat; the said lock being carried in an insulated barrel 18, having yielding contact members 19—20 mounted therein to which the branches of the circuit wire 14 are attached.

The lock comprises a revolvable barrel 21, which carries at its inner end a projecting pin 22, which is adapted when the barrel is turned to a locked position to engage the contact member 19, so that the two contact 95 members 19—20 which are normally disengaged, may be brought in contact and an unbroken line formed between the battery and coil.

Mounted within the hood 1 in any suitable 100 position preferably on the side frame adjacent the lower end of the steering post 4, is a block 25 which carries contact plates 26—27 that are insulated from each other and provided with binding posts 28—29 respectively, to which circuit wires 30—30' are connected; the wire 30 also being connected with the negative pole of the battery and the wire 30' with a pole of the coil 16, so that with the lock closed, a circuit may be closed 105 from the battery through wires 14—30 and 30' to energize the coil 16.

Connected with the throttle lever 5 and with the contact plate 26, is a cable 36 which is of such a length and the lever 5 so positioned that when the throttle is closed the lever 5 will draw the cable taut to draw the plate 26 out of engagement with the plate 27, so that a circuit through the coil will be broken, but when the throttle is opened the cable is slackened and the members 26—27 contact each other and close the circuit through the coil.

Suspended above the coil core 38 on a spring arm 39 that is secured to the side of the housing 13, is a metallic rod 40, the end 15 of which carries a disk 41; the rod being so placed with relation to the coil that when a circuit is passed through the coil, the latter is energized and the disk 41 and rod 40 are magnetically drawn downwardly toward the core 38 so that contact pins 43—44 20 extending from the said rod are brought in contact with plate 45—46 respectively that are carried on supporting partitions 47—48 within the housing 13 and provided near 25 their free ends with adjusting screws 45'—46' and at the fixed ends with binding posts 49—50.

Connected with the spring arm 39 by means of a binding post 51 is a circuit wire 30 52 which connects also with the circuit wire 30, and connected with the plate 46 by means of the binding post 50 is a circuit wire 55 which connects at its opposite end with the wire 30'.

35 Leading from the poles of the horn motor 9 are wires 56—57, which connect respectively with the binding post 49 and circuit wire 14 so that when a circuit from the battery is closed through wire 14—30 and 40 30', the coil 16 is energized and the rod 40 is magnetically drawn downwardly bringing the pins 43 into contact with plate 45 so that a current is closed from the positive pole of the battery through circuit wires 14, 45 and 57; the horn motor, wires 56, plate 45, rod 40, arm 39, wire 52, and wire 30 to the negative pole of the battery so that the horn motor is energized and the alarm given.

By this arrangement it will be seen that 50 the owner or driver when leaving his car, may turn the lock bolt 21 so that the pin 22 will hold the contact plates 19—20 in contact with each other and by closing the throttle the lever 5 is thrown back to tighten 55 the cable 36 and disengage the plate 26—27. Should any one then attempt to start the car it is necessary that the throttle lever be turned to open the throttle. On doing this the cable is slackened which will permit a 60 contact of the plates 26—27 and a circuit is closed through the coil as previously described which will energize the same to draw the bar 40 downwardly to complete a circuit through the horn mechanism which will 65 give an alarm to the owner.

In order to likewise alarm the owner should any one attempt to open the hood doors 2, I provide blocks 60 which are insulated from and mounted at either side of the hood and carried thereby are spring plates 70 62—63; that are held disengaged by posts 64—65 on the doors 2.

The posts being so positioned that when the hood doors are closed, they will depress the plates 63 to disengage the same from the 75 plates 62 and break a circuit therethrough, but on raising the doors the plates 63 are allowed to spring upwardly to contact the plate 62.

Connected with binding posts 66—67 on 80 the plates 62—63 are circuit wires 68—69 which lead respectively to wires 30 and 30', so that when the lock parts are engaged should any one raise a hood door, the plates 63 will engage the plate 62 and a circuit is 85 closed through the coil from the positive pole of the battery through wires 14—30'—69 plates 62—63, wires 68 and 30 to the negative pole of the battery which will energize the coil to magnetically draw the rod 40 90 downwardly to again close a circuit through the horn motor to give an alarm as previously described.

I also provide a means for giving an alarm should any one attempt to remove the batteries from their housings. This means comprises the spring arms 75—76 having binding posts 77—78 to which are connected by circuit wires 79—80 leading respectively to the wires 30—30'; the arms 75—76 being 100 held disengaged when the box lid is closed by a bolt 82 projecting from the said lid, but should the bolt be removed so that the lid be raised, the bolt releases the spring arm 76 allowing it to contact the arm 75 and a 105 circuit is closed through the coil from the positive pole of a battery through wires 14—30' 80, arms 76—75, wires 79—30 to negative pole of battery, which will energize the coil to close a circuit through the 110 horn motor to operate the same as previously described.

With the parts so arranged it will be seen that should the owner of a car equipped with my invention wish to leave the same, he may 115 set the alarm by turning the lock barrel 21 to such a position that the pin 22 thereon will cause the contact member 19 to engage the member 20. The contact members carried on the blocks 25, 60 and 61 are normally held disengaged respectively by the throttle arm 5 and hood door posts 64—65, but should any one attempt to open the throttle or to raise a hood door, a circuit will be closed from the battery to the horn 120 motor and the same will continue to operate to alarm the owner until he, or one with a suitable key, turns the lock bolt to release the contact plates 19—20 to break the circuit.

It is apparent that with a device of this character a simple and compact means is provided whereby an automobile owner is protected against theft of the car and as the parts and their connecting wires may be concealed or placed in conduits they cannot be tampered with or disconnected.

Having thus described my invention, what I claim as new therein and desire to secure by Letters-Patent, is:—

10 1. The combination with an automobile having a hood, hood doors, and a throttle mechanism, of a signaling system comprising a battery, a signaling mechanism having electrical connection with the said battery, means connected with said throttle mechanism and means on said hood doors for closing or breaking said electrical connection through the said system and a lock for

20 breaking or closing a connection with said signaling mechanism.

25 2. The combination with an automobile having a hood, hood doors, and a throttle mechanism, of a signaling system comprising a battery, an electrically operated signaling mechanism having electrical connection with said battery, a pair of contact plates adjacent each of said hood doors interposed in said electrical connection, a post on each of said doors for holding said plates

30 disengaged when said doors are closed, a

pair of contact plates interposed in said electrical connection adjacent said throttle mechanism, means connected with said throttle mechanism for breaking or closing a circuit through the last named contact plates and a lock interposed in said connection between said signal and battery having contact members thereon and means in said lock for holding said contact members engaged for

35

the purpose set forth.

3. The combination with an automobile having a hood, hood doors, and a throttle mechanism, of a signaling system comprising a battery, an electrically operated signaling mechanism having electrical connection with said battery, a pair of contact plates adjacent each of said hood doors interposed in said electrical connection, a post on each of said doors for holding said plates

45

disengaged when said doors are closed, a pair of contact plates interposed in said electrical connection adjacent said throttle mechanism, means connected with said throttle mechanism for breaking or closing a circuit

50

through the last named contact plate, and a relay operable by the battery for closing a circuit through said signaling mechanism and battery.

In testimony whereof I affix my signature.

CHARLIE O. LOUTHAN.
